UNITED STATES PATENT OFFICE.

HANS SENGBUSCH, OF CHICAGO, ILLINOIS, ASSIGNOR, BY MESNE ASSIGNMENTS, TO AUTOMATIC ELECTRIC INC., OF CHICAGO, ILLINOIS, A CORPORATION OF DELAWARE.

AUTOMATIC TELEPHONE-SWITCHING APPARATUS.

Application filed August 27, 1925. Serial No. 52,731.

My invention relates to step-by-step switching apparatus employed in automatic telephone exchanges, and is concerned, more particularly, with a new and improved 5 switching mechanism of the type commonly known as a "selector", that is to say, a switch employed for automatically selecting and making connection with an idle trunk line leading to another selector or to a "connector", as the case may be.

Such apparatus as intimated above are disclosed in the patents to Keith, Erickson and Erickson, Nos. 815,176 and 815,321, both granted March 13, 1906. Although the 15 switches described in these patents have no immediate bearing upon the present invention, the presentation of the case will be greatly facilitated if the known is vividly recalled, before an attempt is made to apprehend the new. I shall therefore give a 20 brief account of the salient features and operations of the well known rotary and vertical switch shown and described in detail in the above patents.

The essential mechanism consists of a longitudinally and axially movable shaft provided with wipers adapted to engage the terminals of trunk lines which are arranged in terminal banks in groups in horizontal 30 semi-circular rows or levels.

The switch as a whole involves suitable electromagnetically-actuated mechanism for stepping the shaft vertically upwards, thereby positioning the wipers opposite a 35 certain row of terminals containing the desired trunk or line, whereupon the shaft is moved radially to select the trunk or line within that group. In case of a selector, the vertical movement is controlled by the 40 calling subscriber operating the usual calling device and the rotary movement takes place automatically, while in a connector both movements are under the calling subscriber's control.

The release of the switch is accomplished 45 upon the subscribers abandoning the call and replacing their receivers, whereupon the release magnet energizes causing the shaft to rotate back by force of a spiral spring and 50 to drop then vertically into its normal position by force of gravity.

Summarizing the features of the usual vertical and rotary switch, which should be kept in mind in examining the present in-

vention, the shaft, or rather, to say, the 55 wipers describe an angular motion, viz, vertically upwards, horizontally within a certain level and back again, during release, along the same paths, each movement being controlled by a distinct and separate magnet. The switch is thus provided with three 60 operating magnets, the vertical, the rotary and the release magnet, each executing solely the respective operation of the mechanism.

The principal object of the present invention is to reduce the production cost and the maintenance expenses of the mechanism by simplifying its operations and, consequently, 65 eliminating sources of trouble.

It will be seen presently that my invention 70 represents a complete departure from the usual, that is to say, that I employ entirely different and novel principles for operating the mechanism. The most conspicuous features, however, which distinguish my improved switch from the old and well known apparatus will now be outlined.

I have adopted the usual terminal banks in which the contacts of trunks or lines are 75 arranged in groups in horizontal rows or levels. This, of course, necessitates a vertical and rotary movement of the shaft carrying the usual set of wipers. The novel features will therefore be found in the manner 80 of positioning the wipers upon a desired set 85 of contacts associated with a trunk line.

Instead of moving the shaft vertically upwards under the control of a special vertical magnet, to position them opposite a desired row of contacts, I utilize gravitational force directly controlled by an operating magnet which absorbs the current impulses produced by the subscribers' calling device and moves a barrel provided with helically arranged steps or notches. The 90 shaft carrying the wipers is provided at its upper end with a cam which is normally resting upon that barrel and advances vertically downwards in a step-by-step movement in accordance with the displacement 95 of the notches by the revolving barrel relative to the supporting cam. In other words, the shaft rests upon the uppermost tooth of a plurality of teeth helically arranged on a circular member, and the support is withdrawn in a step-by-step movement of said member relative to the shaft 100 support, permitting the shaft to advance 105

vertically downwards by force of gravity. The helically arranged teeth of the revolving barrel will thereby pass the supporting cam of the shaft, but the cam cannot take hold in any of the passing teeth due to the speed of the barrel and the inertia of the shaft. Upon the cessation of the movement of the barrel, the cam attached to the shaft will engage the tooth corresponding to the number of steps taken. The wipers are now positioned opposite the desired level of bank contacts.

The rotary movement commences then, automatically in case of a selector and under directive control in case of a connector. The rotary impulses are delivered to the same magnet as before, and the barrel provided with helically arranged teeth, advances again, in the same direction. However, the cam secured to the upper part of the shaft, is now inserted in one of the teeth, and the shaft follows therefore, the rotary movement, advancing the wipers along the contacts of the selected level, to select an idle trunk or a subscriber's line, as the case may be.

The release of the switch is accomplished by again delivering current impulses to the same magnet and thereby continuing the rotary movement of the barrel and also of the shaft, advancing the wipers along the remaining contacts of the level. A projecting arm, secured to the shaft, will strike a helical runway shortly after the last contact set in a row is passed, and lift the shaft out of attachment with the revolving barrel, i. e., the cam provided at the upper part of the shaft, which took hold in a tooth upon termination of the vertical movement, will disengage that tooth. The rotary, restoring operation of the barrel continues while the shaft rests with the projecting arm on the helical runway. This arm is provided with a pin extending vertically upwards and adapted to be engaged by a release lever, forcing the arm and with it the shaft, to travel diagonally up along the helical runway into its normal position.

A spiral spring, having one end secured to the spring housing which is firmly attached to the drum and the other end to a release lever which rests against a stop, stores up energy during the rotation of the barrel, gradually increasing the tension of the release lever against the stop. This stop will be removed momentarily shortly before the final step is taken by the barrel, i. e., shortly before the barrel completes a full circle of 360 degrees. Accordingly, the release lever being set free, it will turn under the tension of the spiral spring, and, as has been intimated above, it will catch the pin secured to the projecting lever mounted on the shaft which at this instance is resting upon the helical runway, and carry the

shaft up into its normal resting position. The switch is now ready for subsequent use.

The above description which is necessarily incomplete on account of its brevity, will be amplified in the detailed explanation which is yet to follow, and the operations of the mechanism will appear more clearly. However, it will be seen from the above that I have eliminated two operating magnets while the functions of the apparatus are fully preserved. In other words, I employ in my improved switch only one single operating magnet as compared with three separate magnets in the usual apparatus, and accomplish the same results without impairing the reliability of the operations. It will be apparent later on that there are a variety of other features and objects apart from those suggested in the foregoing paragraphs.

35 I shall now present a detailed description of my invention and shall refer thereby to the attached drawings which form a part of this specification.

30 In Fig. 1, I have shown the interior of the switch mechanism as seen from the terminal banks, with the banks removed;

Fig. 2 is a side view of the switch illustrated in Fig. 1, showing also a cross section of the terminal banks;

Fig. 3 illustrates the same switch as seen from the top;

Fig. 4 is a cross section of the barrel and of the guide and release mechanism shown in the upper part of Figs. 1 and 2;

Fig. 5 illustrates the interlocking release mechanism in detail as seen from line A—A in Fig. 4;

Fig. 6 shows the working of the guide mechanism as seen from line B—B of Fig. 4;

Fig. 7 shows the relation between the guide lever and the release mechanism after the setting of the switch and before release;

Fig. 8 is a detailed view of the wiper 110 guide lever;

Fig. 9 is a detailed view illustrating the manner of securing the release lever to the spring housing; and

Fig. 10 shows a schematic circuit for operating the switch.

Like parts being numbered alike in the drawings Figs. 1-9, inclusive, I shall, in the course of the following discussion, refer to a certain figure only if necessary for a clear understanding. Fig. 10 will be explained separately. I have not gone into a detailed illustration of the method of mounting the switch and the banks on the supporting frame or rack, but merely indicated the manner of mounting in order to simplify the drawings and the description.

Referring now to the drawings, it will be seen that the shaft 1 is provided, at its upper end, with a cam 2 having a projection

3. Secured to the upper plate 4 of the U-shaped switch frame 5 is a bearing 6 as can best be seen in the cross-section Fig. 4. A member 7 extends through bearing 6. 5 The upper, barrel or drum-shaped, part of member 7 is provided with helically arranged teeth 8 in number corresponding to the levels of the terminal banks. The shaft rests suspended by projection 3 of cam 2 upon the incline 9 of the barrel 7, i. e., just 10 in front of the first tooth. The lower end of member 7 extends through the bearing 6 and has secured to it the spring housing 10. The member 7 is thus adapted to be moved radially but not longitudinally. Inserted in the 15 spring housing 10 is a spiral spring 11 and the release lever 12. A loose connection is maintained between the spring housing 10 and the release lever 12 by spiral spring 11 which is secured to the spring housing at 20 its outer end and to the release lever at its inner end.

The release lever 12 is provided with a circular groove 66. Two semi-circular washers 67 and 68 shown in Fig. 9, are inserted in said groove and secured to the spring housing 10 by means of a cap 69, as can readily be seen from drawing Fig. 4. This arrangement is provided for keeping 25 the release lever 12 in its proper place and permits an easy detachment. As will appear more clearly later on, when the barrel 7 rotates, the spring housing 10 participates in the movement. The release lever 12, however, cannot take part in the 30 rotary movement of the drum because it rests against a stop 13 of an angular release member 14. The spiral spring 11 will, therefore, be wound up during the rotation 35 of drum 7 and gradually increase the tension of the release lever 12 resting against stop 13.

The shaft 1 extends through the barrel 7 and through the release lever 12 inserted in the spring housing. Rigidly fastened to the shaft by means of screw 15 is the shaft-guide lever 16 provided with a pin 17 which is positioned in front of the release lever 12. The guide lever 16 is normally resting 40 against a stop 18.

The sequence of events will be brought out clearly as the description progresses. However, it will be advisable now to consider the vertical movement of the shaft and the 45 operation of the shaft guide-lever 16, before proceeding with the description of details.

It will be assumed for this purpose that current impulses are delivered to the magnet designated 29 for rotating the barrel member 7 in a direction indicated by arrows in Fig. 3. As is shown in Fig. 1, the shaft is normally resting with the projection 3 of cam 2 upon the incline on barrel 7 preceding 50 the first tooth. Upon the barrel taking its first step, this support is withdrawn from

the shaft cam, moving the shaft vertically upwards due to the incline at the normal position, i. e., the shaft is started with a tendency to move upwards, whereupon it drops vertically down due to gravitational force. 70 If no other steps were taken by the barrel 7, that is, if only a single impulse were delivered to magnet 29, the shaft would drop down and projection 3 of cam 2 would engage the first tooth of the barrel 7, which tooth corresponds to the first level of the terminal banks. However, if a plurality of current impulses is delivered to the magnet, the barrel 7 continues to rotate rapidly in a buzzer-like manner, and the shaft advances 80 vertically downwards by force of gravity. The projection 3 of cam 2 cannot engage any of the passing teeth due to the high speed of the barrel and the relative inertia of the shaft. Upon the termination of the vertical 85 impulses, the projection 3 of cam 2 will engage the tooth corresponding to that level.

The shaft is guided during its vertical movement, by the guide lever 16, and the description of its function will best be followed 90 by consulting Figs. 2, 4-7, inclusive. The end of the shaft guide-lever 16 is provided with a semi-circular groove 19. Opposite this groove, just below and in line with it there is a roller 20 fastened to an angular support 21, which is pivoted upon member 22, the latter also furnishing the stop 18. A spring 23 keeps the roller 20 in alignment 95 with shaft guide-lever 16. Upon the support being withdrawn, the shaft commences 100 to move vertically downward. The shaft guide-lever 16 passes stop 18 but takes hold upon the guide-roller 20 by means of the semi-circular groove 19. By this arrangement, the shaft is smoothly guided in its 105 vertical motion, and proceeds vertically downwards. The shaft extends through the lower plate 24 of the frame and is provided, at its lower end, with a set of wipers designated 25, 26, and 27. The wipers are in 110 this manner advanced vertically and positioned opposite a desired row of bank contacts. Pin 17 secured to the shaft guide-lever 16 is thereby vertically displaced relative to the locked release lever 12. 115

Continuing the description of the mechanical details of the apparatus, it will be seen that the barrel member 7 is provided with a circular row of teeth indicated at 28. A magnet 29 located in front of the U-shaped switch frame 5 and permanently fastened to it, is adapted, when energized, to attract its armature 30 pivoted at 31. This armature is provided with a dog 32 extending towards the circular row of teeth associated 120 with barrel 7, and held in normal position by means of spring 33 with its front part engaging a tooth. Stop 34 is provided for limiting the movement of the dog 32, and 125 detent 35 for preventing the barrel from falling 130

ing back during rotation. A cam 36 is permanently fastened to drum 7 provided for operating the off-normal spring set 37. The off normal springs will be operated, i. e., contacts 38 and 39 will be closed and contacts 40 opened with the first step taken by the barrel, the direction of the movement being indicated by the arrows. Upon the barrel completing a full circle of 360 degrees, the off normal springs will be operated again and brought into the position shown in the drawing Fig. 3. The armature 30 is also provided with a projecting arm 41 holding an insulated pin 42, which extends through an opening 43 towards a pair of normally closed contacts 44. As will be seen later on, these contacts are located in the circuit of magnet 29 and will produce current impulses for automatically operating the magnet to execute the hunting movement of the wipers after they have been advanced vertically and positioned opposite a certain level. During the vertical movement of the wipers, these contacts, although operated, will be ineffective. Underneath the circular row of teeth, and secured to the barrel 7 is a pin 45. The purpose of this pin is to momentarily move the release lever 14 shortly before the termination of the restoring movement of the barrel, and its operation can best be explained by referring to Figs. 4 and 5.

It will be seen that the pin 45 is normally located in front of the restoring lever 14 which is kept in a normal position by spring 46, with the stop 13 engaging the release arm 12 and preventing the latter from following the rotary motion of the barrel as explained previously. The pin 45 advances with the barrel in a direction indicated by the arrow in Fig. 5. Upon the barrel taking its last step, i. e., upon its return to normal, the pin approaches the lever arm 14 from the other side, as indicated in dots, and lifts the lever momentarily, thereby removing stop 13 and allowing the release arm 12 to effect the restoration of the shaft in a manner to be presently explained.

The semi-circular member 64, which is sloping helically upwards and fastened to the lower plate 24 of the switch frame, one of the fastening screws being visible at 65, serves for restoring the switch shaft into its normal position, and shall be conveniently termed "helical-restoring-runway", or shortly "helical runway". I shall next describe these restoring operations, referring particularly to Fig. 2. Details, however, will best be seen in Figs. 5, 6, and 7.

In order to explain the restoring operations of the switch, it will be assumed that the wipers have been positioned opposite a desired row of contacts as described. This vertical setting is followed by the rotary movement of the shaft which is effected in

a similar manner as was the vertical motion, i. e., the magnet 29 will again operate and rotate the barrel 7. At this time, however, the projection 3 of cam 2 of the shaft will have engaged the tooth corresponding to the selected row of contacts, and the shaft will, therefore, participate in the rotary movement and advance the wipers along the contacts of the level in search for an idle trunk. The guide lever 16 follows the rotary movement of the shaft, disengaging the guide roller 20 and moving towards the helical runway. In following these operations with the help of Fig. 2, the rotary motion of the guide lever 16 with its associated pin 17 must be visualized as taking place towards the observer. When an idle trunk is encountered, in case of a selector, or the wanted line in case of a connector, the rotary movement ceases and the switch remains in the attained position throughout the duration of the call. The guide lever 16 and the release lever 12 will be in a position relative to each other, as shown in Fig. 7.

When the subscribers replace the receivers at the termination of the call, the magnet 29 energizes again and rotates the barrel 7 as before. The wipers advance along the remaining contacts in the level, at this time, however, without any effect, and the guide lever advances towards the helical restoring runway 64.

It should be observed at this point, that the restoring operation presents an advantage which is not to be under-estimated. In the usual switch the wipers return to normal along the setting paths. This, of course, results in an uneven wear of contacts, i. e., the first few contacts will wear out more quickly than the contacts at the end of the levels causing a variety of troubles, which can, in some cases, only be remedied by replacing the partly worn banks by new ones. This expensive procedure is obviated in my improved switch, as all contacts receive equal wear.

Continuing the description of the restoring operations, the guide lever 16 advances towards the helical runway 64 and strikes this runway shortly after the wipers have passed the last terminal set of the level. The guide lever 16, being forced against the incline of the runway 64 will lift the shaft, and the projection 3 of the shaft cam 2 disengages from the tooth of the barrel. The latter continues to rotate, while the shaft, with its guide levers 16 engaging the runway is carried vertically upward, since a portion of the barrel member 7 engages the cam 3. Upon the barrel taking its last step, i. e., upon completing a circle of full 360 degrees, the pin 45 located underneath the ratchet part of the barrel, approaches the interlocked restoring lever 14 as shown in Fig. 5 and previously explained, and moves

the lever 14 and with it the stop 13 momentarily, whereupon the release lever 12 is set free under force of the spiral spring 11, advancing in the direction indicated by the arrow in Fig. 7. The release lever 12 will catch the pin 17 associated with the shaft guide 16 which is at this instance upon the highest portion of the helical runway, and carry the shaft guide 16, and with it the shaft, into normal position, where the shaft guide 16 engages the stop 18 and the release lever 12 the stop 13, while the projection 3 of the shaft cam 2 is positioned again upon the incline of the barrel preceding the first helical tooth. The switch is now ready for subsequent use.

As will be recalled, the connections between the wipers and the operating circuits are maintained in the usual switch, by means of a flexible, insulated three-conductor cord, which follows the movement of the wipers. This arrangement is impractical in the present switch, in view of the fact that the wipers describe a full circle of 360 degrees. In order to maintain the required connections, I have devised auxiliary wipers which follow the movements of the switch wipers. It will be seen from the drawings Figs. 1 and 2 that I have provided a shaft 47 which is longitudinally movable in bearings 48 and 49. One of these bearings is located in the lower plate 24 of the switch frame while the other is associated with an angular holder 50 attached to the back of the frame. The auxiliary wiper 51 consists of a pair of conductively connected springs extending between the two springs of the private or test wiper 25, and is fastened to the shaft 47 by means of an adjustable clamp 52. Auxiliary wipers 53 and 54 serve in a like manner for maintaining the connections with the line wipers 26 and 27, respectively, and are, of course, insulated from each other. These latter wipers are secured to the shaft 47 by means of a clamp 55, which is shown separately in Fig. 8. The clamp has a forked projection extending into a groove 56 provided upon the line-wiper holder 57 which is rigidly fastened to the shaft 1 by means of a screw 58. The private or test wiper 25 is also rigidly fastened to the shaft 1 by holder 59 and screw 60. The auxiliary wipers will, as can readily be seen, move up and down in synchronism with the switch wipers, and no interference will occur during the rotary movement of the latter. The conductors will be attached to the terminals 61, 62 and 63 of the auxiliary private and line wipers, respectively.

I shall now explain the manner of mounting the switching apparatus upon a supporting frame or rack, as indicated in Figs. 1 and 2. As will be seen from these figures, the switch rests on two circular bars 70 and 71 extending through the lower plates of

the individual switch frame, and having turned down projections extending through the upper plate, where they may be fastened by means of nuts. The rack consists essentially of two angle irons 72 and 73, which are fastened to the uprights in the usual manner. Clamps, such as 74 and 75 are provided for rigidly attaching the circular bars 70 and 71 holding the switch, to the angle irons of the supporting rack. The line terminal banks 76, and the test terminal banks 77 are secured to the bars 70 and 71 as usual, by means of clamps.

It will be apparent that the switch can be easily removed from its terminal banks and mounted again by merely loosening two nuts securing the mechanism to the circular supporting bars associated with the rack. It will also be obvious from the foregoing, that my improved switch presents many advantages not found in other apparatus. The switch as a whole, as well as each of the parts within a switch, permits easy adjustment because of being readily accessible, and proper operation is insured due to the simplicity of the mechanism.

I shall now explain the circuit shown in Fig. 10. The sequence of operation will thereby appear more clearly, and points which were not plainly brought out during the discussion of the mechanical details, will obviously suggest themselves in the course of the following considerations.

Referring now to Fig. 10, the circuit shown is designed for a switch as described above, where the apparatus works as a selector switch, i. e., a switch accessible to the subscriber's individual line switch or to another selector, and adapted to select an idle trunk in a certain group of trunks, located in horizontal rows or levels, and leading to other selectors or to connectors.

When this switch is taken for use by a line switch or by a preceding selector, as the case may be, the line relay 20 operates over a circuit including its two windings, armatures 11 and 14 of the switching relay 10, and the trunk conductors 5 and 7. Armature 21 closes a circuit for the slow acting release relay 30. Relay 30 energizes and closes its armature 31, thereby preparing a circuit for the stepping relay 50; at armature 32, the slow relay 30 connects ground to the release trunk conductor 6 and to a junction point between switching relay 10 and a contact of said relay, and at armature 33, the slow relay 30 prepares the path for the vertical directive impulses for operating the motor magnet 60. When the calling subscriber operates his calling device in accordance with a digit in the desired party's number, he interrupts the circuit of the line relay 20. This relay deenergizes a number of times corresponding to the dialled digit, and transmits, at each deenergization, a ground

impulse to the motor magnet 60. The first impulse transmitted by the line relay 20 may be traced from ground at armature 13 of the switching relay, armature 21 and its resting contact, upper winding of the slow acting series relay 40, armature 33 and its working contact, off normal springs 70, winding of the motor magnet 60 to battery. The release relay 30 does not return to normal during the rapid transmission of impulses due to its sluggish properties. The series relay 40, which is also slow acting, energizes upon the transmission of the first impulse and attracts its armature 41, preparing a circuit for the stepping relay 50, and closes its armature 42, substituting another path for the further transmission of impulses, excluding off normal springs 70, which opened responsive to the first energization of the motor magnet 60 and consequent rotation of the barrel member provided with helically arranged teeth. Off normal springs 72 close also upon the first step of the motor magnet, preparing a circuit for the stepping relay 50. This circuit will be closed from ground at armature 41 and its working contact, off normal springs 72, interrupter springs 61 operated by the motor magnet, winding of the stepping relay to battery, upon each deenergization of magnet 60, but the circuit will not produce any changes during the delivery of the vertical impulses to the motor magnet 60, except that the stepping relay, at its armature 51, prepares a holding circuit for its own winding.

As will be remembered, the operation of the motor magnet is effective to the barrel carrying helically arranged teeth. Accordingly, the barrel rotates, and the shaft moves vertically downward advancing the wipers to the desired row of contacts. The shaft, being provided with a projecting cam which advances vertically along the helically arranged teeth is prevented from engaging any of the passing teeth due to the rapidly revolving barrel. Upon the termination of the directive impulses, however, the cam takes hold in the tooth directly below and the shaft thus positions the wipers opposite the desired level, and couples itself with the barrel member. A subsequent rotation of the barrel will therefore result in a rotation of the shaft and of the wipers.

This subsequent rotation is initiated automatically upon the termination of the vertical impulses and takes place as follows. The motor magnet 60 deenergizes after the last directive impulse and closes its interrupter springs 61. The stepping relay 50 energizes now over a circuit including armature 41 and locks itself in a circuit including the interrupter springs 61, off normal springs 72 and its own armature 51 and its working contact to ground at armature

32. The stepping relay attracts armature 52, preparing a circuit for the motor magnet, which circuit is completed by the normally closed contact operated by armature 41, upon the deenergization of the slow acting series relay 40, which deenergizes shortly after the last impulse had been delivered to the motor magnet. The motor magnet energizes over this circuit and rotates the barrel by one step. The shaft, being at this time firmly attached to the barrel, due to the projecting cam engaging the helical tooth corresponding to the selected level, will therefore advance the wipers into engagement with the first set of bank contacts. Upon energizing, the motor magnet 60 opens its interrupter springs 61, thereby opening the locking circuit of the stepping relay 50. Relay 50 deenergizes thereupon and opens at its armature 52 the circuit of motor magnet 60 which deenergizes also, again closing its interrupter contact 61. The stepping relay 50 cannot energize over its original circuit due to armatures 41 and 51 being open. The further operation depends now whether the seized trunk is busy or idle. If idle, the switching relay 10 operates immediately and switches the line conductors through to the next switch. For the purpose of explanation, however, it shall be assumed that the trunk is busy.

Ground will be encountered by test wiper 76 and stepping relay 50 energizes again over a circuit including armature 12 and its resting contact, armature 31 and its working contact, off normal springs 72, interrupter springs 61 and winding of the stepping relay to battery. A short circuit is connected around the switching relay 10 at the same time, preventing it from energizing. This short circuit includes ground at armature 32, winding of the switching relay 10, working contact and armature 31, resting contact and armature 12 to ground encountered by the test wiper 76. Upon energizing, the stepping relay closes a locking circuit for its own winding, over its armature 51, and an operating circuit for the motor magnet at its armature 52. The wipers advance to the next set of bank contacts. These mutual operations between motor magnet 60 and the stepping relay 50 will be continued until an idle trunk is found.

Assuming this trunk to be the one shown in the drawing and designated 78, 79 and 80, there will be no ground encountered by test wiper 76, and the stepping relay 50 will not energize. The switching relay 10, however, being no longer short-circuited, operates from ground at armature 32, its winding, off normal springs 72, interrupter springs 61, to battery over the winding of the stepping relay 50. The latter cannot energize at this time, due to the high resistance of the switching relay.

Upon energizing, the switching relay 10 connects the trunk conductors through at its armatures 11 and 14, thereby deenergizing line relay 20; disconnects the test wiper 76 from the original circuit and connects it directly to the junction point of its own winding and the release trunk conductor 6, at its armature 12; and disconnects ground from the release circuit at its armature 13. The slow acting relay 30 deenergizes and removes ground from the release trunk conductor 6 and from the switching relay 10 at its armature 32, and prepares the initiation of the release at its armature 33. The seized switch, however, connected ground to the test conductor immediately upon being taken into use in a similar manner as the present switch by means of a slow acting relay such as relay 30, and this ground is therefore propagated back over the test conductor and test wiper 76 to the release trunk 6 leading to the preceding switch. The switching relay 10 remains in operated position throughout the duration of the call being connected to ground at the release trunk and to battery in series with the stepping relay 50 over off normal springs 72 and interrupter contacts 61. The stepping relay does not operate in this circuit due to the high resistance of the switching relay.

The calling subscriber operates his calling device in accordance with the remaining digits in the desired party's number, setting the various selectors and finally the connector to establish connection with the wanted line terminals. No change occurs in the present switch during the operation of the subsequent apparatus or during the time the subscribers carry on a conversation. The subscribers replace their receivers at the termination of the call, causing the removal of ground potential from the release trunk conductor and consequent release of the various switches. When the ground is removed from the release trunk, the switching relay 10 deenergizes, restoring its armatures to the positions shown in the drawing. The line relay 20 and the slow relay 30 being deenergized at this time, a circuit will be closed for the operation of relay 40 from ground at armature 13, armature 21 and its resting contact, upper winding of relay 40, armature 33 and its resting contact, off normal springs 71, and to battery over the lower winding of relay 40. Relay 40 energizes and attracts its armature 41, thereby completing a circuit for stepping relay 50, which circuit includes armature 41, off normal springs 72, interrupter contacts 61, and winding of relay 50 to battery. Upon energizing, relay 50 completes a circuit for the motor magnet 60 from ground at armature 32 and its resting contact, working contact and armature 52,

and motor magnet 60 to battery. The motor magnet operates and interrupts the circuit of relay 50 at its interrupter contact 61, whereupon relay 50 deenergizes, interrupting the circuit of the motor magnet 60 at its armature 52. Accordingly, the motor magnet releases also, again closing the circuit of the stepping relay, and the stepping relay in turn, again closes the circuit of the motor magnet.

This mutual operation between the stepping relay and the motor magnet continues, and the motor magnet rotates the barrel again. A short survey of the circuit will reveal that the operations of the stepping relay and of the motor magnet depend upon the conditions of the off normal springs 71 and 72. As long as these contacts are closed, the operations are bound to continue, due to relay 40 being energized and maintaining ground connection at armature 41 for the operation of relay 50 which in turn depends on the closure of off normal springs 72. The motor magnet, in operating, rotates the barrel and the off normal springs will be operated and switched to normal as shown in the drawing, upon the barrel completing its circle of 360 degrees, preventing any further movement.

The shaft, carrying a cam at its upper end provided with a projection which, at the time engages one of the helically arranged teeth, participates in the rotation and advances the wipers over the remaining terminals in the level, however, without any effect, due to the armature 31 being open at this time, i. e., the test wiper 76 is on an open circuit and cannot test any of the trunks. Recalling the mechanical operations occurring during the restoring rotary movement of the barrel, it will be remembered that the shaft is provided with a guide lever which proceeds towards a helical restoring runway. This guide lever strikes the runway shortly after the wipers have passed the last terminal set in a level and lifts the shaft and with it the projection of the shaft cam out of engagement with the helical tooth on the revolving barrel. The latter continues to rotate and the shaft rests with the guide lever engaging the helical upwards sloping runway. Upon the barrel taking its last step, it operates the off-normal contacts as described, preventing any further rotation, and moves a restoring lever momentarily, which releases a special arm. The latter rotates under the force of a spiral spring, catches the guide lever of the shaft and moves it upwards into its normal position, along the incline of the helical runway. At the end of the restoring movement of the shaft, the shaft guide lever and the special restoring arm engage their respective stops, while the projection of the shaft cam is again posi-

tioned upon the barrel in front of the first helical tooth. The switch is now at normal and may be used for a subsequent call.

Although I have illustrated and described 5 a particular switch embodying the principles of my invention, it is to be understood that I do not wish to limit myself to such use. The principles involved obviously lend themselves to wide application in a variety 10 of fields without departure from the spirit of my invention.

What I claim as my invention is:

1. An automatic switching mechanism having a vertically and radially movable shaft 15 provided with wipers, terminals arranged in horizontal rows accessible to said wipers, an electromagnet having only one pawl operated thereby, means including said electromagnet and pawl for moving said wipers vertically to select a certain desired row, and for then moving said wipers radially to select certain terminals within said row, said means also operative for moving said wipers into normal position.
2. An automatic switching mechanism having a vertically and radially movable shaft provided with wipers, terminals arranged in horizontal rows accessible to said wipers, an electromagnet, means including 25 said electromagnet for moving said wipers vertically under directive control to select a certain row, and for then moving said wipers automatically to select certain terminals within said row, said means also operative 30 for moving said wipers step by step into normal position.
3. An automatic remotely controlled switching mechanism having a shaft provided with wipers, terminals accessible to 40 said wipers, means including an electromagnet for moving said shaft first longitudinally and then axially to establish a temporary connection between said wipers and certain of said terminals, said means 45 also operative for then moving said wipers back into normal position, said wipers describing a circle of 360 degrees, whenever used for establishing a connection.
4. An automatic remotely controlled 50 switching mechanism having a shaft provided with wipers, terminals accessible to said wipers, means including an electromagnet for effecting a longitudinal directly controlled movement of said shaft executed by force of gravity, said means also operative for automatically effecting a radial movement of said shaft to position said wipers upon certain terminals, and again operative for moving said wipers in the 55 same radial and opposite longitudinal direction into its normal position.
5. An automatic remotely controlled 60 switching mechanism having a shaft provided with wipers, terminals accessible to said wipers, means including an electromag-

net for effecting a longitudinal directly controlled movement of said shaft executed by force of gravity, said means also operative for automatically effecting a radial movement of said shaft to position said 70 wipers upon certain terminals, and mechanical means controlled by said electromagnet for moving said wipers in opposite longitudinal and in the same radial direction into 75 normal position.

6. In automatic remotely controlled switching mechanism having a shaft provided with wipers, terminals accessible to said wipers, means including an electromagnet for effecting a longitudinal directly controlled movement of said shaft executed by force of gravity, said means also operative for automatically effecting a radial movement of said shaft to position said 80 wipers upon certain terminals, and mechanical means released by said electromagnet for moving said wipers in the same radial direction into 85 normal position.

7. In automatic remotely controlled switching mechanism having a shaft provided with wipers, terminals accessible to said wipers, means including an electromagnet for effecting a longitudinal directly controlled movement of said shaft executed by force of gravity, said means also operative 90 for automatically effecting a radial movement of said shaft to position said wipers upon certain terminals, and mechanical means operating independently of said 95 electromagnet for moving said wipers in the 100 same radial direction into normal position.

8. In automatic remotely controlled switching mechanism having a shaft provided with wipers, terminals accessible to said wipers, means including an electromagnet for effecting a longitudinal directly controlled movement of said shaft executed by force of gravity, said means also operative 105 for automatically effecting a radial movement of said shaft to position said wipers upon certain terminals, and mechanical means operable independently of but controlled by said electromagnet for moving 110 said wipers in the same radial direction into 115 normal position.

9. In automatic remotely controlled switching mechanism having a shaft provided with wipers, terminals accessible to said wipers, means including an electromagnet for effecting a longitudinal directly controlled movement of said shaft executed by force of gravity, said means also operative 120 for automatically effecting a radial movement of said shaft to position said wipers upon certain terminals, and mechanical means operable independently of and after said electromagnet has ceased to operate for moving said wipers in the same 125 radial direction into normal position.

10. In automatic remotely controlled 130

- switching mechanism having a shaft provided with wipers, terminals accessible to said wipers, means including an electromagnetic for effecting a longitudinal directively controlled movement of said shaft executed by force of gravity, said means also operative for automatically effecting a radial movement of said shaft to position said wipers upon certain terminals and again operative for moving said wipers in the same radial direction from said terminals, and mechanical means for restoring said wipers to normal position.
11. In an automatic remotely controlled switching mechanism, terminals arranged in groups in horizontal rows, a shaft provided with wipers longitudinally movable by gravitational force to select a certain row and axially movable to select terminals within said row, and a single electromagnetic means for controlling and executing the movements of said shaft, including its restoring movements.
12. In an automatic remotely controlled switching mechanism, a plurality of terminals, wipers movable in two dimensions provided for establishing connection with said terminals, said wipers being locked in a normal position while not in use, and a single electromagnetic means operative for executing the movements of said wipers in establishing connection with certain of said terminals and again operative for restoring said wipers to normal position.
13. In an automatic remotely controlled switching mechanism, a set of terminals, wipers resting in a normal position out of engagement with said terminals, and a single electromagnetic means operative for successively moving said wipers in two directions to engage said terminals and again operative for restoring said wipers to normal position by moving them in like and opposite directions.
14. In an automatic remotely controlled switching mechanism, a set of terminals, wipers resting in a normal position out of engagement with said terminals, and a single electromagnetic means operative for successively moving said wipers in two dimensions to engage said terminals and again operative for restoring said wipers to normal position, said restoring movement involving different paths than the setting movement.
15. In an automatic remotely controlled switching mechanism, a set of terminals, wipers resting in a normal position out of engagement with said terminals, and a single electromagnetic means operative for successively moving said wipers in two dimensions to engage said terminals and again operative for restoring said wipers to normal position, said wipers describing a circle of 360 degrees for every connection.
16. In a switching mechanism, terminals, wipers resting in a normal position out of engagement with said terminals, a single electromagnetic means operative for successively moving said wipers in two dimensions to engage certain of said terminals, the movement of the first dimension being executed by force of gravity but under control of said electromagnetic means, said electromagnetic means being again operative for restoring the wipers to normal position over different paths than those employed in the setting movements.
17. In a switching mechanism, a shaft provided with wipers, terminals of trunk lines arranged in groups in horizontal rows accessible to said wipers, a member provided with a row of helically arranged notches, directly controlled means for moving said member radially to advance said shaft longitudinally by force of gravity to position said wipers opposite a certain row, said shaft being out of engagement with said member during said movement, means on said shaft for engaging said member at the end of said directly controlled movement, means for then operating said member to continue its radial movement to advance said wipers horizontally to select an idle trunk, and mechanical means for restoring said shaft to normal position.
18. In a switching mechanism, a shaft provided with wipers, terminals arranged in groups in horizontal rows accessible to said wipers, a radially movable member provided with a circular row of teeth, said member being operable under directive control for effecting a longitudinal movement of said shaft executed by force of gravity to position said wipers opposite a certain row and also operable automatically for effecting an axial movement of said shaft to position said wipers upon certain terminals within said row, and again operative for restoring said shaft to normal position.
19. In a switching mechanism, a shaft provided with wipers, terminals arranged in groups in horizontal rows accessible to said wipers, a radially movable member provided with a circular row of teeth, said member being operable under directive control for effecting a longitudinal movement of said shaft executed by force of gravity to position said wipers opposite a certain row, and also operable automatically for effecting an axial movement of said shaft to position said wipers upon certain terminals within said row, and again operative for restoring said shaft to normal position, said wipers describing a circle of 360 degrees.
20. In a switching mechanism, a shaft provided with wipers, terminals arranged in groups in horizontal rows accessible to said wipers, a radially movable member provided with a circular row of teeth, said member

being operable under directive control for effecting a longitudinal movement of said shaft executed by force of gravity to position said wipers opposite a certain row, and 5 also operable automatically for effecting an axial movement of said shaft to position said wipers upon certain terminals within said row, and again operative for initiating the restoring movement of said wipers to 10 normal position, said restoring movement taking place over different paths than the setting movement and involving mechanical means operative independently of and after said member provided with circular teeth 15 has restored to normal.

21. In a switching mechanism, terminals, wipers movable in two dimensions and normally resting out of engagement with said terminals, a single motion operating member, a device for storing up mechanical tension, means for operating said member to store up energy in said device and to move said wipers into temporary engagement with terminals, and means controlled by said member for releasing said energy to effect the restoring movement of said wipers.

22. In a switching mechanism, terminals, wipers movable in two dimensions and normally resting out of engagement with said terminals, a single motion operating member, a device for storing up mechanical tension, means for operating said member to store up energy in said device and to move said wipers into temporary engagement with terminals, and means controlled by said member for releasing said energy to effect the restoring movement of said wipers, said wipers describing a circle of 360 degrees whenever used for establishing a connection.

40 23. In a switching mechanism, terminals, wipers movable in two dimensions and normally resting out of engagement with said terminals, a single motion operating member, a device for storing up mechanical tension, means for operating said member to store up energy in said device and to move said wipers into temporary engagement with terminals, and means controlled by said member for releasing said energy to 45 effect the restoring movement of said wipers, said restoring movement taking place in a direction continuous to the setting movement of said wipers.

55 24. In a switching mechanism, terminals arranged in groups in horizontal rows, a shaft provided with wipers longitudinally movable to select a certain row and axially movable to select terminals within said row, a radially movable member for controlling 60 the movements of said shaft including the restoring movement, a lever arm, a spiral spring associated with said member and said lever arm, means for operating said member to effect the setting operation of said shaft and for storing up energy in said

spiral spring, and means for releasing said energy stored up by said spiral spring to effect the restoring movement of said wipers, said restoring movement taking place in the same direction as the rotary setting 70 movement.

25. In a switching mechanism, terminals, vertically and horizontally movable switching members for establishing temporary connections with said terminals, said members resting in a normal position out of engagement with said terminals, a member provided with a circular row of teeth movable only radially in one direction for controlling the movements of said wipers, a 80 lever arm, a spiral spring attached to said member and said lever arm, means for operating said member to effect the vertical and horizontal setting movements of said wipers and for storing up energy in said 85 spiral spring, and means controlled by said member for releasing said energy to effect the restoring movements of said wipers, said wipers describing a circle of 360 degrees.

26. In a switching mechanism, terminals, wipers movable in two dimensions and normally resting out of engagement with said terminals, an operating device, means for actuating said device to move said wipers into temporary engagement with terminals, 95 an obliquely ascending semi-circular track, and means controlled by said operating device for restoring said wipers to normal along said track.

27. In a switching mechanism, terminals, wipers movable in two dimensions and normally resting out of engagement with said terminals, an operating device, means for actuating said device to move said wipers into temporary engagement with terminals, 100 a helically ascending runway, and means released by, but operating independently of said operating device for restoring said wipers to normal along said runway.

28. In a switching mechanism, terminals, wipers movable in two dimensions and normally resting out of engagement with said terminals, an operating device, means for actuating said device to move said wipers into temporary engagement with terminals, a 110 helical incline, and operations initiated by said operating device for effecting the restoration of said wipers to normal along said incline, said restoring movement being continuous to said setting movement.

120 29. In a switching mechanism, terminals, wipers movable in two dimensions and normally resting out of engagement with said terminals, an operating device, means for actuating said device to move said wipers into temporary engagement with terminals, a helical continuous incline, and means controlled by a step-by-step movement of said operating device for effecting the restoration of said wipers to normal along said 125 130

continuous incline, said wipers describing a circle of 360 degrees.

30. In a switching mechanism, terminals, wipers movable in two dimensions and normally resting out of engagement with said terminals, an operating device, means for actuating said device to move said wipers into temporary engagement with terminals, a helically ascending guide track, and 10 mechanical means operatively effective to the exclusion of said operating device for restoring said wipers to normal position along said guide track, said restoring movement involving different paths than the setting movement.

31. In a switching mechanism, terminals, wipers resting in a normal position out of engagement with said terminals, and means operative for moving said wipers successively in two dimensions to temporarily engage terminals and again operative to restore said wipers to normal position in a continuous helical motion.

32. In a switching mechanism, terminals, wipers resting in a normal position but out of engagement with said terminals, and means operative for moving said wipers successively in two dimensions to temporarily engage terminals and again operative to restore said wipers to normal position in a continuous helical motion, said wipers describing a circle of 360 degrees.

33. In a switching mechanism, terminals, wipers resting in a normal position but out of engagement with said terminals, and means operative for moving said wipers successively in two dimensions to temporarily engage terminals and again operative to restore said wipers to normal position in a continuous helical motion, said restoring movement being in a direction continuous to the setting movement.

34. In a switching mechanism, terminals arranged in groups in horizontal rows, a plurality of movable stops, a shaft provided with wipers and resting in a normal position suspended on one of said stops, means for successively moving said stops with relation to said shaft, said shaft moving vertically by force of gravity in accordance with the movement of said stops and engaging at the termination of said movement the stop corresponding to the number of steps taken, positioning said wipers opposite a desired row, said means again operative for moving the stop engaged to said shaft to advance said wipers horizontally within said row to select terminals.

35. In a switching mechanism terminals arranged in groups in horizontal rows, a plurality of helically arranged stops, each corresponding to a certain row, provided on

a circular radially movable member, a shaft carrying wipers and resting suspended upon said member in a normal position preceding said stops, means for moving said member to displace said stops relative to said shaft for advancing said shaft vertically by force of gravity, said shaft engaging at the termination of said movement the stop corresponding to a certain row, positioning said wipers opposite thereto, said means again operative for moving said member to operate said shaft radially to advance said wipers to engage certain terminals within said row.

36. In a switching mechanism, terminals arranged in groups in horizontal rows, a radially movable member provided with helically arranged stops one for each row, a shaft carrying wipers and resting suspended upon said member in a normal position preceding said stops, means for moving said member under directive control to successively advance said stops with relation to said shaft for moving said shaft vertically by force of gravity, said shaft at the termination of said directive movement engaging the stop corresponding to a certain row positioning said wipers opposite thereto, said means then operative for moving said member automatically to successively advance the stop engaging said shaft to move said wipers into engagement with certain terminals within said row.

37. In a switching mechanism, a wiper set having a plurality of wipers rotatable through arcs of 360 degrees in each of a plurality of planes, and means for maintaining a continuous electrical connection to said wipers.

38. In a switching mechanism, a wiper set rotatable in a continuous direction in each of a plurality of planes, and means for maintaining a continuous electrical connection to said wiper set.

39. In a switching mechanism, a shaft carrying wipers, means for moving said shaft longitudinally and for rotating it through an arc of 360 degrees, and means for maintaining a continuous electrical connection to said wipers.

40. In a switching mechanism, a shaft carrying wipers, means for moving said shaft longitudinally and for rotating it through an arc of 360 degrees, a second shaft parallel to the first and movable longitudinally with it, and means on said second shaft for maintaining a continuous electrical connection to said wipers.

In witness whereof, I hereunto subscribe my name this 25th day of August, A. D., 1925.

HANS SENGBUSCH.
